UNITED STATES PATENT OFFICE.

HERBERT R. WILSON, OF ROCHESTER, NEW YORK.

LACE HOOK AND CLASP.

SPECIFICATION forming part of Letters Patent No. 700,274, dated May 20, 1902.

Application filed September 20, 1901, Serial No. 75,884. (No model.)

To all whom it may concern:

Be it known that I, HERBERT R. WILSON, a citizen of the United States, residing at Rochester, in the county of Monroe and State of 5 New York, have invented a new and Improved Lace Hook and Clasp, of which the following is a specification.

The object of my invention is to produce a lace-hook that may be raised or opened during the process of lacing and then folded down upon the lace after the lace has been properly placed, so as to hold the lace securely and at the same time present no projecting points when used upon a shoe, such as are likely to 15 catch or engage the lower edges of ladies' skirts.

My improved hook and clasp has other uses as well as on shoes. It may be used upon corsets or upon any articles which it is desired 20 to secure by means of a lace where it is desirable that such lace shall be readily disengagable from the article.

The accompanying drawings, illustrating my invention, are as follows:

25 Figure 1 is a top view of my hook and clasp with the lace-engaging portion opened or raised. Fig. 2 is a top view of my hook, but with the lace-engaging portion folded down. Fig. 3 is a side view of the parts seen in Figs. 1 and 2 so arranged as to show the under side of the lace-engaging portion or cap. Fig. 4 is a side view of the parts seen in Figs. 1 and 2 and with the lace-engaging portion raised. Fig. 5 shows a portion of a shoe with my lacing-hooks thereon and with the upper four of 35 such hooks and clasps in their open or raised position. Fig. 6 shows a portion of a corset or other similar article with a series of such lacing hooks and clasps, a number of which to the right in the figure are seen in their open or raised position. Fig. 7 shows an enlarged 40 sectional view of one of my lacing-hooks with the portion of the lace secured thereby, such sectional view also showing one form of spring *f*, by means of which the parts may be held in position.

Similar letters refer to similar parts throughout the several views.

Referring to the drawings, my hook and 50 clasp consists of a folding cap-piece *A*, to which there is hinged in the well-known way found in lever-buttons the stem *a*. The lower

end of this stem *a* is formed into an eyelet *b*, of substantially the usual form. By means of this eyelet the hook and clasp may be secured to 55 the shoe or other article in the same manner that eyelets are usually secured or in the way the ordinary hooks are secured on gentlemen's shoes. In case at any time the cap-piece should become disengaged from the eyelet the 60 eyelet may be used to perform its usual function. The stem *a* is so hinged to the cap-piece *A* that the parts when open or closed shall be caused to occupy and be securely held in substantially the position shown in the drawings 65 by means of the spring *f*, located within the cap-piece *A*. On the under surface of this cap-piece *A* is formed a flange *e*, which is cut away over a short portion of the periphery of the cap-piece *A* and just over the eyelet *b*. 70 The lace *c* is arranged to be located and held in the space between the cap-piece *A* and the eyelet *b* or the surface of the shoe or article which is practically even therewith and also in the opening left in this flange *e*, whereby 75 when the cap-piece *A* is forced downward to its closed position, as indicated in Fig. 2, the lace is firmly held by the cap-piece *A*, the ends of the flange *e*, and the eyelet *b* or surface of the article to which such eyelet is attached.

In lacing up any article upon which my hooks and clasps are used, such hooks and clasps are all opened up, so that they will occupy the positions indicated by the upper 85 four clasps seen in Fig. 5 or in the eight of such clasps seen at the extreme right in Fig. 6. Then the lace is passed around such hooks in such a way as to come beneath the ends of the flange *e* and in the space between the ends 90 of such flange and the body of the article to be laced. In this way the lacing is done as with ordinary hooks, such as found on gentlemen's shoes. When the lace has been placed in position upon all the hooks, the cap-pieces 95 *A* are all turned down, so as to securely hold the lace in the desired position. If desired, one of such laces may be carried a second time around one of the hooks at the end of the article, as indicated at the hook at the 100 right-hand side of the top of the shoe in Fig. 5, serving to firmly hold the lace without tying.

Attention is called to the fact that the stem

and cap-piece take the place of the ordinary lacing-hook, and in addition thereto when the cap-piece is down the projections formed thereon, consisting in the ends of the flange 5 on such cap-piece, serve to clamp the lace against the stem. In order to guard against the cap-piece being accidentally raised, it is preferred to use a flange which shall be continuous except at a point opposite the stem 10 rather than to use projections on the cap-piece.

What I claim is—

1. A lacing hook and clasp consisting of a cap-piece articulating with an eyelet, such 15 eyelet and cap-piece connected together by means of a stem hinged to such cap-piece, and a spring operating to hold such cap-piece relatively to such stem either in its open or

closed position as desired, such cap-piece carrying two projections arranged to come on 20 each side of such stem.

2. A lacing hook and clasp consisting of a cap-piece articulating with an eyelet, such eyelet and cap-piece connected together by means of a stem hinged to such cap-piece, 25 and a spring operating to hold such cap-piece relatively to such stem either in its open or closed position as desired, a discontinuous flange on such cap-piece with the two ends thereof arranged to come on each side of such 30 stem.

HERBERT R. WILSON.
